CHILD'S ROCKING CHAIR

Radcliffe W. Hunter, 533 E. 33rd Place, Chicago, Ill., and Stephen E. Konecnik, 1135 Broadway, Park Ridge, Ill.

Filed Aug. 22, 1961, Ser. No. 66,461

Term of patent 14 years

(Cl. D15—1)

FIG. 1

We claim:

The ornamental design for a child's rocking chair, as shown.
